Electronic Systems Integration Inc.,**
Nashua, NH (US)

Primary Examiner — Rosemary K Tarcza

Assistant Examiner — Nathaniel D Buckner

(74) **Attorney, Agent, or Firm:** Sand & Sebolt

(**) **Term:** **14 Years**

CLAIM

The ornamental design for an data storage transfer archive
repository, as shown and described.

(21) **Appl. No.:** **29/496,221**

DESCRIPTION

(22) **Filed:** **Jul. 10, 2014**

FIG. 1 is a perspective view of a data storage transfer archive
repository showing our new design;

(51) **LOC (10) Cl.** **14-02**
(52) **U.S. Cl.**

FIG. 2 is a second perspective view thereof, showing the
locations of detail views FIGS. 2A-2C;

USPC **D14/356**

FIG. 2A is an enlarged detail view thereof;

(58) **Field of Classification Search**

FIG. 2B is a second enlarged detailed view thereof;

USPC D14/300-302, 314, 348-370, 383-385,

FIG. 2C is a third enlarged detailed view thereof;

D14/435, 496, 135, 155, 299, 180, 140.4;

FIG. 3 is a front elevation view thereof;

D13/103, 119, 162, 184, 199; D10/65,

FIG. 4 is top plan view thereof;

D10/75, 78; D9/432, 434; D3/273

FIG. 5 is a right side elevation view thereof;

CPC G11B 20/1833; G11B 33/125; G11B

FIG. 6 is a left side elevation view thereof.

33/128; G06F 1/187; G06F 1/20; G06F
3/0689

FIG. 7 is a perspective view of a data storage transfer archive
repository showing a second embodiment of our new design;

See application file for complete search history.

FIG. 8 is a second perspective view thereof, showing the
locations of detail views FIGS. 8A-8C;

(56) **References Cited**

FIG. 8A is an enlarged detail view thereof;

U.S. PATENT DOCUMENTS

FIG. 8B is a second enlarged detailed view thereof;

D208,859 S * 10/1967 Dublin et al. D13/184

FIG. 8C is a third enlarged detailed view thereof;

D307,423 S 4/1990 Hill

FIG. 9 is a front elevation view thereof;

5,515,515 A 5/1996 Kennedy et al.

FIG. 10 is top plan view thereof;

5,913,926 A 6/1999 Anderson et al.

FIG. 11 is a right side elevation view thereof; and,

D431,241 S * 9/2000 Armstrong D14/348

FIG. 12 is a left side elevation view thereof.

D433,382 S * 11/2000 Lytel D13/123
